UNITED STATES PATENT OFFICE.

JOHN L. NILSON AND OLOF G. NILSON, OF CHICAGO, ILLINOIS.

SAFETY-RAZOR.

1,159,075.

Specification of Letters Patent.

Patented Nov. 2, 1915.

Application filed March 23, 1914. Serial No. 826,598.

To all whom it may concern:

Be it known that we, JOHN L. NILSON and OLOF G. NILSON, citizens of the United States, residing at Chicago, in the county of 5 Cook and State of Illinois, have invented certain new and useful Improvements in Safety-Razors, of which the following is a specification.

Our invention relates to safety razors and 10 its object is to provide means for imparting to the hand-operated type of this type of razor the saw or endwise draw movement and to improve the construction and arrangement of the blade-holding portion of 15 the device.

With this object in view the invention consists in the novel construction, combination and arrangement of parts hereinafter described in detail, illustrated in the accompanying drawing and incorporated in the appended claims.

In the drawing—Figure 1 is a perspective view of a safety razor embodying our invention with parts of fingers of the right 25 and left hands showing the manner in which a blade is released or inserted. Fig. 2 is a section taken substantially on line 2—2 on Fig. 3. Fig. 3 is a bottom plan view of the razor. Fig. 4 is a view similar to Fig. 2 30 with part of the handle broken away, showing the blade-holding clamp open or the blade released. Fig. 5 is a section taken substantially on line 5—5 of Fig. 2. Fig. 6 is a section taken substantially on line 6—6 on 35 Fig. 2.

In the several views 2 represents a fork-like frame and 3 is a handle having thereon a stud 4 which is fixedly secured in a bore in said frame and has a projecting end on 40 which is mounted an anti-friction roller 5 which engages a slot 6 in the rear portion of a reciprocating blade-holder or razor head 7 supported on said roller and on a pair of pins 8 and 9 secured to and projecting inwardly from the fork-members of the frame or support 2. In the ends or sides of the 45 holder 7 are bores 10 and 11 which engage the pins 8 and 9 loosely to permit movement on said pins. The blade-holder may be a single piece of metal bent seven times to 50 form two nearly alike and relatively movable parts 12 and 13 overlying each other and terminating in jaws 14 and 15 between which the razor-blade, 16, is held. For the 55 purpose of illustrating the parts the mem-

bers 12 and 13 are shown as two separate pieces secured together by means of screws or rivets 17 and 18, each member then being a plate of metal bent three times as shown in Figs. 1, 2 and 4, the slot 6 being formed 60 in the vertical portions of these members which are secured together by the screws 17 and 18. Through top of the holder 9 are bored holes 19 which lighten it and facilitates its cleaning. Its members 12 and 13 65 are made of spring metal and arranged to leave a space 20 (Fig. 4) between the jaws 14 and 15. These jaws are clamped together upon the blade 16 by means of a cam-lever 21 mounted in a slot 22 and having a 70 widened portion 23 between the members 12 and 13 which, when rotated at right angles to their sides, forces them apart thereby drawing together the jaws 14 and 15 as in Fig. 2 which shows the locked position of 75 the lever whereas Fig. 4 shows its released position.

The guard of the razor is a roller 24 journaled on needle-point bearing-ends of the pins 8 and 9 which preferably have threaded engagement with threaded bores in the member 3 whereby they are made adjustable. Thus the roller 24 rotates on the ends of the pins while the holder 7 slides back and forth on them. The sliding movement is 80 caused by a cam-slot 25 in the periphery of the roller and a small wheel 26 secured to a shaft 27 having point bearings in cone-shaped apertures in screws 28 and 29 having threaded engagement with bores in the 85 sides of the holder 7. The periphery of the roller may be suitably knurled or indented by slots to increase its friction-hold upon the face of the user when this is deemed necessary. However the resistance offered 90 to the rotation of this roller is so comparatively slight that a smooth roller may answer the purpose just as well. In Fig. 1 95 31 and 32 may represent forefinger and thumb of the left hand holding the blade 16, while 33 represents the thumb of the right hand pressing up to close the jaws, or pressing down to open the jaws, on the lever 21, 34 and 35 being two right hand fingers coöperating with the thumb in holding the 100 handle 3. As shown in Fig. 3 the ends of the blade 16 project slightly beyond the sides of the holder, which facilitates the adjustment of the blade between the jaws.

In operation the drawing of the roller 110

guard over the face causes the razor blade to reciprocate endwise in a sawing motion, thus making the shaving smooth and easy and making it possible to shave with a comparatively dull blade. Skill from practice is necessary to operate an ordinary razor-blade properly, and the present invention is designed to effect the combined movements automatically.

10 Having thus described our invention we claim as new and desire to secure by Letters Patent—

1. In a safety razor, the combination of a razor head consisting of substantially a single piece of metal bent to form a roller-containing head having co-acting parts which are blade-holding jaws, axial supports for a roller guard upon which said head is reciprocally movable, a handle for said axial

supports, a lever actuating said jaws, and 20 means for reciprocating said head.

2. In a safety razor, the combination of a blade-holder with a frame provided with a handle, said holder consisting of two relatively movable members which are blade-holding jaws and a roller-guard housing, the roller-guard within said housing, axial supports for said roller-guard, means for actuating said jaws, and means for reciprocating said holder. 25

In testimony whereof we have hereunto set our hands in the presence of two subscribing witnesses.

JOHN L. NILSON.
O. G. NILSON.
